SHRINK TUNNEL PACKAGING APPARATUS

Bernard Katz, Greenwich, Conn. (½ Tele-Sonic-Trescott,
a division of Empsco, Inc., 18-35 38th St., Long
Island City, N.Y. 11105)

Filed Feb. 28, 1975, Ser. No. 554,103

Term of patent 14 years

Int. Cl. D15—99

U.S. Cl. D55—1 C

Fig. 1.

Fig. 2.

Fig. 3.

Fig. 4.

FIG. 1 is a perspective view of a shrink tunnel packaging apparatus showing my new design;

FIG. 2 is an elevational view of one end of the apparatus;

FIG. 3 is a front elevational view thereof; and

FIG. 4 is an elevational view of the other end of the apparatus.

I claim:

The ornamental design for a shrink tunnel packaging apparatus, as shown.
